UNITED STATES PATENT OFFICE.

JOHN PLAYER, JR., OF OAKLAND, CALIFORNIA.

ANTICREEPER.

974,821.

Specification of Letters Patent.

Patented Nov. 8, 1910.

Application filed April 12, 1910. Serial No. 554,912.

To all whom it may concern:

Be it known that I, JOHN PLAYER, Jr., a citizen of the United States, residing at Oakland, in the county of Alameda and State of California, have invented certain new and useful Improvements in Anticreepers, of which the following is a specification.

The construction, application and operation of my improved anticreeper are herein fully set forth, reference being had to the accompanying drawings which form a part hereof and in which—

Figure 1 is an end elevation of my improved anticreeper, the base and a portion 15 of the web of the rail to which it is attached being also shown. Fig. 2 is a side elevation of my anticreeper, showing a portion of a tie against which one member of the anticreeper abuts in its restraining action. Fig. 20 3 is a section on line III III of Fig. 1. Fig. 4 is a side view of the rail-gripping jaw. (This is the left-hand jaw of Fig. 1.) Fig. 25 5 is a plan view of the tie-abutting jaw, looking in the direction of the arrow V in Fig. 2. (This is the right-hand jaw in Fig. 1.)

The same reference letters indicate identical parts in all the views.

As will readily be seen from an inspection of the drawings, my anticreeper consists of 30 two interlocking members 1 and 2, which are designed to bear against the lateral edges of the base of the rail 3 and to co-operatively exert a clamping action thereon. In addition to said lateral clamping action, jaw 1 35 also exerts a vertical gripping action upon the upper and lower faces of the contiguous portion of the rail-base, which will be presently explained, and because of this gripping action, said jaw 1 will be herein referred to as the "gripping jaw."

In addition to the lateral clamping action of jaw 2, the lower end of said jaw is adapted to abut or bear against a cross-tie 4 of the track, in a manner and for a purpose 45 which will presently be explained; and because of this abutting function, jaw 2 will be referred to as the "abutting jaw," as by the use of these terms the two members will be clearly and concisely differentiated, especially in the claims, should it be found desirable to employ them thus.

The construction, in detail, of my anticreeper is substantially as follows: The gap of the gripping jaw 1 is provided with con-

vex, opposing, rail-engaging faces 5 and 6 55 which lie obliquely to the respective upper and lower surfaces of the rail-flange or base against which they bear. Said gap is also obliquely inclined, vertically, as a whole, to the longitudinal dimension of the rail- 60 flange, as will be clearly seen by a reference to Fig. 4, which causes the anticreeper to assume an obliquity of position with reference to the rail when affixed thereto, and to extend obliquely downward toward the tie 65 against which it abuts, so that the lower portion only of the anticreeper bears against the tie. The faces 5 and 6 bear firmly against the top and bottom of the contiguous portion of the rail-flange respectively 70 and exert a gripping action upon the rail, and because of this gripping action, the creep of the rail tends to carry jaw 1 with it. This tendency of jaw 1, and more specifically the upper portion thereof, to move with 75 the rail, together with the abutment of the lower portion of jaw 2 against the tie and restraining such movement, tend to cause a rocking movement of the jaws, and this tendency to rock causes the faces 5 and 6 to 80 more firmly bear against the upper and lower faces of the rail base and to increase the vertical gripping action of this jaw upon the rail flange. The contact points of the faces 5 and 6 are staggered, the contact 85 point of the upper face 5 being somewhat in advance of the contact point of the lower face 6 so that the rocking tendency aforesaid causes said points of contact to more firmly grip the rail between them. The 90 abutting jaw 2 is also provided with a gap, the upper lip 7 of which bears against the upper surface of the rail-base, but this jaw does not bear against the bottom of said base. The upper surface or lip 7 of said 95 gap is obliquely convex, the same as jaw 1, but serves principally as a retaining means to keep the jaws in position.

The interlocking features of the jaws 1 and 2 are constructed as follows: Jaw 1 100 is provided with a T-shaped slot or gap 8, adapted for the reception of the T-shaped head 9 of jaw 2; the impinging faces of said slot and head are obliquely inclined relative to the longitudinal dimension 105 of the rail 3, so that when the jaws are placed in engagement or the interlocking position, they are drawn together so that

they clamp the edges of the rail-base between them. The inclination of the impinging faces of said interlocking device is clearly shown in Figs. 3 and 5.

5 In placing my anticreeper in service upon the rail, the abutting jaw 2 is first placed in position with the lower portion thereof abutting against a tie. 4. The gripping jaw 1 is then placed in position and interlocked with jaw 2 by striking it several blows with a hammer or sledge upon the striking boss 10, and this, because of the obliquity of the impinging faces of the interlocking device aforesaid, causes the jaws to firmly bear 15 upon the edges of the rail-base and clamp said base between them. The jaws are so designed that when they are interlocked upon the rail, they will stand in about the relative position shown in Figs. 2, 3 and 5, so 20 that the gripping jaw 1 is farther from the tie than the abutting jaw and cannot come in contact therewith.

The direction of creep of the rail, relative to the position of the anticreeper, is toward 25 the tie, as indicated in Fig. 2, and as the creep of the rail tends to carry the anticreeper with it, and the abutment of jaw 2 against the tie counteracts and restrains this 30 tendency, there is thus set up a tendency of the anticreeper to rock upon the rail-flange, this causes the opposing points 5 and 6 of the jaw 1 to grip the flange or base of the rail more firmly between them, and this 35 action in turn causes a more decided tendency of jaw 1 to move with the rail and a more complete interlocking of the jaws. It will thus be seen that all the stresses brought to bear upon my anticreeper in 40 actual service tend to increase its efficiency and restraining or anticreeping action upon the rail.

I claim—

1. In an anticreeper the combination of 45 two interlocking members co-operatively clamping the rail-base laterally between them, a gap in one of said members, staggered points of contact upon the opposing faces of said gap adapted to bear upon the upper and lower faces respectively of said 50 rail base, the lower end of the other jaw being disposed to abut against a tie, whereby

the creeping tendency of the rail tends to impart a rocking action to the anticreeper.

2. In an anticreeper the combination of 55 two interlocking members arranged to co-operatively clamp the rail base between them, a gap in one of said members adapted to receive one edge of the rail base, staggered points of contact upon the opposing faces of said gap arranged to bear upon the 60 upper and lower faces of said rail base, the lower end of the other jaw being disposed to abut against a tie, the interlocking device of said jaws having obliquely inclined impinging faces, so that the creeping tendency 65 of the rail will cause said members to more firmly interlock.

3. In an anticreeper the combination of 70 two interlocking members arranged to clamp the rail base laterally between them, an obliquely-inclined gap in one of said members adapted to receive one edge of the rail base and to cause the anticreeper to assume a vertical obliquity of position, there 75 being staggered points of contact upon the opposing faces of said gap, the lower end of the other jaw being adapted to abut against a tie whereby the creeping tendency of the engaged rail will tend to impart a 80 rocking action to the anticreeper and cause said points of contact to more firmly bear upon the rail base.

4. In an anticreeper the combination with 85 a rail and a tie of two interlocking jaws adapted to clamp the rail base laterally between them, a gap in one of said jaws adapted for the reception of one edge of the rail base, staggered points of rail contact in 90 said gap whereby the anticreeper is caused to assume a vertically oblique position, the other jaw being arranged to bear at its lower end against said tie whereby the restraining action of the anticreeper will 95 tend to cause it to rock and said contact points to more firmly bear against the rail.

In testimony whereof I affix my signature in presence of two witnesses.

JOHN PLAYER, JR.
